THRESHING

Elmer E. Wickersham, Stockton, Calif., assignor
by mesne assignments, to Caterpillar Tractor
Co., San Leandro, Calif., a corporation of Calif-
ornia

Application January 14, 1928, Serial No. 246,697

20 Claims. (Cl. 130—27)

My invention relates to machines for threshing grain and is especially related to that type of machine ordinarily termed a combined harvester-thresher, including a header portion for cutting 5 the grain and a separator portion for threshing the grain.

An object of my invention is to provide a threshing machine of light but sturdy construction.

Another object of my invention is to provide 10 a unitary body for the separator portion in order to eliminate the large amount of machinery, labor and fitting necessary to assemble the body portion of threshing machines as at present constructed.

A further object of my invention is to provide 15 a metal body sufficiently strong to be self-supporting and at the same time to be of materially less weight than a comparable body built according to the present methods.

An additional object of my invention is to design 20 a threshing machine in which the separator portion is substantially balanced on its supporting axle.

A further object of my invention is to provide 25 a combined harvester-thresher which can be entirely supported by a single pair of wheels.

An additional object of my invention is to improve 30 generally the header portion of a combined harvester-thresher to reduce its cost of manufacture and to afford a construction which is well able to withstand the jolts and jars to which such machinery is customarily subjected.

My invention possesses other advantageous 35 features, some of which with the foregoing will be set forth at length in the following description where I shall outline in full that form of the threshing machine of my invention, which I have selected for illustration in the drawings accom- 40 panying and forming part of the present specification. In said drawings I have shown one form of threshing machine embodying my invention, but it is to be understood that I do not limit myself to such form since the invention, as set forth 45 in the claims, may be embodied in a plurality of forms.

In said drawings:

Fig. 1 is a plan view of a combined harvester-thresher constructed according to my invention. 50 Fig. 2 is a longitudinal section through the threshing machine, the plane of section being indicated by line 2—2 of Fig. 1.

Fig. 3 is a transverse section through the threshing machine of my invention, the plane of 55 section being indicated by line 3—3 of Fig. 2.

Fig. 4 is a transverse section, the plane of section being taken on line 4—4 of Fig. 2.

Fig. 5 is a similar transverse section, the plane of section being indicated by line 5—5 of Fig. 2.

In its preferred form, the machine of my invention preferably includes a separator body 5 made of a tubular shell of corrugated metal.

While the machine is well adapted for use in a wide variety of circumstances and while its construction is susceptible to numerous variations 10 to adapt it to particular circumstances, it is particularly applicable for use in cutting standing grain and threshing the grain kernels from the straw. I have therefore constructed, according to one aspect of my invention, a light, strong 15 machine for cutting and threshing standing grain.

I preferably provide a pair of supporting 20 wheels 6 and 7 held in axial alignment by an axle 8 preferably of tubular cross section. Resting on the axle 8 are a pair of balance beams 9 and 10 of the usual kind extending to the rear of the axle where they are provided with a counterweight 12 to balance a header 13. This header customarily comprises a draper 14 and a 25 spout 16 over which the draper is extended. The leading edge of the header is customarily provided with a sickle bar, not shown, driven by a suitable shaft 17. This shaft extends to a gear cluster 18 driven by a tumbler shaft 19 in the 30 customary fashion. Preferably the entire header is balanced on the axle 8 and a convenient mode of construction is to situate the balance beams 9 and 10 on opposite sides of the supporting 35 wheel 6.

Also mounted on axle 8 is the body 21 of the threshing machine. These bodies are customarily made of a framework of wood or of iron shapes which is suitably covered with sheet metal and require a separate main frame to support 40 them on the wheels. They require special jigs and a considerable amount of close fitting and hand labor in assembling, and are prone to work loose under the jarring and jolting to which the machine is subject in use. Due to the large 45 number of braces and struts requisite in the ordinary method of construction, the body for the separator is of considerable weight, is costly to transport, and requires a large amount of power to propel in the field.

To overcome these difficulties and to provide 50 a body which is at once light and rigid, I preferably form the body 21 of a tubular shell made of corrugated metal. It is possible to make the shell of a smooth sheet, but then the thickness 55

of metal requisite for a rigid body is such that the weight is excessive. For that reason, I preferably use metal of light section and corrugate it in order to obtain the requisite strength. My 5 corrugated metal shell 21 is not only light, but is possessed of sufficient inherent rigidity to preclude any objectionable flexing in the body.

The shell 21 is preferably mounted by passing the axle 8 transversely therethrough and usually 10 is situated so that when it is provided with its separating machinery the assembly approximately balances on the axle 8. To reenforce the points at which the axle 8 passes through the shell 21, I 15 preferably secure pads 22 and 23 to the shell and form them to encompass the axle 8. Preferably the pads are secured against rotation on the axle but the separator body is free to rock about the axis of the wheels 6 and 7 by rocking with the axle. By this construction no separate 20 main frame is necessary; the sheet metal body serves both as a main frame and as an enclosure and support for the threshing and separating mechanisms.

The leading end of the shell 21 is preferably 25 closed by a head 24 usually of flanged metal fitting within the open end and suitably secured in place, as by rivets. Means are provided for drawing the combined harvester-thresher of my invention over a field and these means usually 30 comprise a draft attachment 28 secured to the lower end of shell 21 and preferably engageable by a tractor, not shown. Intermediate the ends of the shell and spaced from the head 24 is a transverse wall or bulkhead 26 also preferably of 35 metal and suitable secured to the shell. This bulkhead is provided with an aperture 27 to receive portions of the separator mechanism, as will be described later, and is effectively situate adjacent the axle 8 to assist in stiffening the body 40 21 near its point of support.

Intermediate the head 24 and the bulkhead 26 45 is a generally rectangular aperture 29 cut in one side of the shell 21 to receive the spout 16 of the header. A jigger-board of the usual kind can be provided at the lower margin of the aperture 29 if desired, but ordinarily the corrugated shell 21 is amply strong and rigid to support one end of the spout 16.

Within the shell 21, I preferably mount suitable separating mechanism. Thus the shell not 50 only forms a housing or enclosure for the separating mechanism, but it also provides a unitary support therefor. Extending horizontally across the shell 21 and lying just below the aperture 29 55 is a feeder 31 to receive grain from the spout 16. As is customary, this feeder comprises a belt, usually a pair of chains on which suitable transverse sticks 32 are affixed, running about drums 33 and 34 at each end. Below the feeder, I preferably provide a sheet 36 of metal to catch any grain kernels which might possibly become dislodged at this early stage in the separating process.

Just beyond the termination of the feeder and 60 preferably operating through the aperture 27 in bulkhead 26 is a cylinder 37. This cylinder preferably is arranged with its axis substantially transverse of the shell 21 and approximately in vertical alignment with the axle 8. Comprised in the cylinder is a spindle 38 therefor preferably 65 journaled in pads 39 and 40 fastened directly to the walls of the shell so that the entire weight of the cylinder 37 is supported directly by the shell. To aid in guiding grain brought in by the 70 feeder 31 into the cylinder 37, metal cheeks 42

and 43 preferably extend from the sides of the shell 21 along the sides of the cylinders. As a further aid in feeding the grain into the cylinder, a beater 44 of the usual type is journaled within the shell 21 slightly above the feeder and 75 in advance of the cylinder 37.

Cooperating with the cylinder is a concave 46 of the customary kind which is supported within the shell 21. Preferably the concave is vertically adjustable to afford a regulation in the separation 10 of the grain kernels from the straw. In operation, the cylinder 37 is rapidly revolved and discharges the grain in substantially a tangential direction upwardly toward the top of the shell 21. The grain straw emerges from the cylinder 15 in a more or less fluffy, light mass and the mass is further separated and dispersed by a beater 41, similar to one unit of the conventional picker, which is mounted on a central shaft 48 journaled directly in the shell 21.

At a suitable point in the length of the shell, a baffle 49 is preferably suspended to halt the upward progress of the grain and straw and to permit it to fall gravitally onto a straw walker 51.

The straw walker preferably comprises a plurality of parallel strips 52 having serrations 53 on their upper edges. These strips at their leading ends are provided with eccentric straps 54 encompassing eccentrics 55 disposed in varying angular relation on the drive shaft 57. The trailing ends of the strips 52 are mounted for horizontal oscillation on a rod 58 secured to hangers 59 at either side of the shell. Upon rotation of the drive shaft 57, the eccentrics 54 afford a rotary motion of the leading ends of the strip 52 35 and a reciprocating motion of the trailing ends thereof. Due to the varied angular relationship of the eccentrics 55, not all of the strips approach their topmost positions at the same time and action is produced which impels toward the rear 40 of the shell the straw falling on the straw walker. Preferably the strips 52 comprised in the straw walker are not sufficiently numerous to extend entirely across the shell 21 but at their sides lie adjacent walls 61 and 62 provided by a separate 45 insert 63 suitably secured to the walls of the shell and sloping generally downward to a central trough 64 at the lowermost portion of the shell 21.

Means are provided for cleaning the grain kernels shaken and separated from the straw. 50 To suitable ones of the strips 52, a screen 66 is secured and partakes of the motion of those strips. Grain kernels passing through the fluffy straw on the straw walker lodge on the screen 66 and, due to the vibrating motion of the screen 55 in consonance with the motion of the strips 52 to which the screen is attached, usually drop through the screen onto the insert 63 down which they pass gravitally to the central longitudinal trough 64. Weeds and undesirable short lengths 60 of straw which will not pass through the screen 66 discharge over the trailing end thereof and pass out of the machine through the open rear end of the shell 21. The straw from which the grain kernels have been removed and which has 65 been sufficiently agitated by the straw walker is also discharged from the machine through the open end of the shell 21.

The grain which accumulates in the trough 64 is propelled by a grain auger 67 toward the rear 70 of the shell 21 where it falls into the casing 68 of a cross auger 69 leading to an elevator 71. The elevator extends along the outside of shell 21 into the upper part of a bulk grain bin 72. This bin preferably is a rectangular housing 75

having ends with arcuate terminations to seat on the upper portion of the shell 21. The grain discharged by the elevator 11 into the bulk grain bin is first distributed by a cross auger 73 extending transversely of the bin. The housing 14 of the cross auger is provided with an aperture 76 opening onto the initial end of a recleaner screen 77, which is preferably supported on pivots 78 and 79 secured to the walls of the bulk grain bin 72 and usually is oscillated by a lever 81 connected to a suitable crank pin 82. Grain kernels which fall on the recleaner screen are violently agitated while they progress gravitally toward the lower end thereof. Suitable kernels pass through the recleaner screen and fall into a hopper 83 the bottom of which is formed by a sheet metal plate 84 sloping toward a discharge spout 86 extending over wheel 1. Arranged under the spout 86 is usually a sacking platform 87 mounted on the axle 8 and leading to a sacking chute 88 affording a convenient means for releasing sacks of grain from the harvester.

Grain which has not been completely threshed, and undesired seeds which were not separated pass over the end of the recleaner screen 77 to fall gravitally down either one of the two chutes 89 and 90 substantially spanning the beater 44 and opening onto sheets 92 and 93 guarding the two sides of the feeder 31. Such grain kernels are again passed through the threshing operation and eventually are either discharged as unfit or are lodged in the hopper 83 of the bulk grain bin.

It is desirable to assist in the separation of the grain by means of air blasts and these preferably are furnished by a blower 101 conveniently mounted exteriorly of the shell 21 and secured thereto by a saddle 102. An extension of the cylinder spindle 38 passes through the blower 101 and serves to drive the impeller thereof, not shown. An air duct 103 diverges tangentially from the casing of the blower 101 and leads into a transverse pipe 104 extending part way through the shell 21. The pipe for a portion of its circumference is flared into a throat 106 in which is located a regulating butterfly 107 to control the efflux of air. Inasmuch as the throat extends substantially entirely across the shell 21 and directs the air in an upward direction through the screen 66 and past the beater 47, it assists materially in keeping the grain undergoing separation in a light, fluffy condition and is conducive to a thorough separation of grain kernels from the straw.

Also diverging tangentially from the blower casing 101 is an air duct 108 leading upwardly to the bulk grain bin through which a connecting pipe 109 extends. This pipe lies just below the recleaner screen 77 and is provided with a throat 111 for directing the air blast upwardly through the recleaner screen. A damper 112 is hinged to the pipe 109 for regulating the air blast.

A suitable source of power is provided for driving the various parts of the separator mechanism as well as the header mechanism. An engine 113, preferably of the usual internal-combustion type, is suitably mounted on the axle 8. Preferably this engine is slightly rotatable around the axle for adjustment of the driving chain 114 which connects it with a gear 116 at the end of the cylinder and blower spindle 38. Also on the spindle 38 and preferably 75 interposed between the blower casing 101 and

the shell 21 is a sprocket 117 meshing with a drive chain 118 in engagement with a sprocket 119 secured to the shaft 121 of the beater 44. A sprocket 122 similar to sprocket 119 drives a chain 123 passing in turn over sprockets on the shaft of the feeder 31, on the shaft 124 for transmitting the drive to the gear nest 18, on the shaft 57 which actuates the straw walker eccentric, on the shaft 48 of the beater 47, around an idler 126 and back to the sprocket 122. An auxiliary chain 127 is in engagement with a second sprocket on the shaft 57 and meshes with a sprocket 128 on a cross shaft 129 connected by bevel gears 130 to the longitudinal grain auger 67. The trailing end of the auger likewise meshes through bevel gears 132 with a cross shaft 133 at the end of the shell 21 and drives the elevator 11 through a short chain 134. At the upper end of the elevator, there is provided a chain drive extending from the upper elevator shaft to the shaft of the distributing auger 73 and a second chain 137 for driving the crank disc 82.

It will be appreciated that in accordance with my invention a combined harvester-thresher is provided in which the threshing machine is characterized by a tubular corrugated metal body of extremely light weight and rigid non-yielding construction forming not only a housing and support for the separating mechanism but also serving as the main frame of the machine. With this construction I am enabled to dispense with a large number of parts necessary in the usual body and frame construction and am enabled to effect economies in material and manufacture. A compact arrangement is provided, as is evidenced by the simple drive mechanism employed, and inasmuch as the assembly provided by the separator body and the associated separating mechanism is substantially balanced on the supporting axle, it is necessary to provide only the minimum number of ground contacting wheels, thus further reducing the cost of manufacture and increasing the simplicity.

I claim:

1. A thresher comprising a tubular shell, an axle passing through said shell, a pair of supporting wheels on said axle and separating mechanism mounted on said shell substantially to balance the assembly on said axle.

2. A thresher comprising a tubular metal shell, reinforcing pads on opposite sides of said shell, an axle passing through said pads and said shell, and supporting wheels on said axle.

3. A thresher comprising a tubular metal body, a head closing one end of said body, a bulkhead spaced from said head and extending across said body, said body having an aperture therein intermediate said head and said bulkhead, and separating mechanism within said body adapted to receive grain through said aperture and discharge the straw therefrom through the open end of said body, said mechanism including a cylinder adjacent said bulkhead.

4. A thresher comprising a tubular metal shell, a head closing one end of said shell, a bulkhead bracing said shell and spaced from said head, an axle passing through said shell adjacent said bulkhead, supporting wheels on said axle, and separating mechanism within said shell, said mechanism including a cylinder operating through an opening in said bulkhead.

5. In a harvester-thresher a sole support and housing for threshing mechanism consisting of a single member.

6. In a thresher, a main frame consisting of a

sheet of material, and threshing mechanism supported on said frame.

7. In a thresher, a one-piece main frame, and threshing mechanism enclosed by said frame.

5 8. In a thresher, a tubular main frame, threshing and separating mechanism therein, a bin thereon, and a conveyor to transport grain from said mechanism to said bin.

10 9. In a combined harvester-thresher, a one-piece body having an aperture in the side thereof, a header communicating with said aperture, threshing mechanism enclosed in and supported by said body, a wheel-supported axle secured to said body, and a draft attachment secured to 15 said body.

10. In a thresher, a main frame consisting of a sheet of material, and threshing mechanism supported and enclosed by said frame.

11. In a threshing machine, a wheeled axle, a 20 shell constituting the sole frame of the machine, threshing mechanism mounted within and supported by said shell, and means for positioning the shell on the axle in a position in which the shell is substantially balanced about the axle.

25 12. In a threshing machine, a wheeled axle, a unitary sheet metal shell member constituting the sole frame of the machine, threshing mechanism mounted within and supported by said shell, and means for positioning the shell on the 30 axle in a position in which the shell is substantially balanced about the axle.

13. In a thresher, a unitary sheet metal shell member, an axle, means for positioning the shell in a balanced position on the axle, and a grain 35 bin mounted above the axle and upon the shell to preserve the balance of the shell.

14. In a threshing machine, a wheeled axle, a unitary sheet metal shell member constituting the sole frame of the machine, threshing mechanism mounted within and supported by said shell, and means for positioning the shell on the 40 axle.

45 15. In a mobile thresher, a main supporting frame consisting essentially of a substantially rigid unitary and hollow structure, thresher mechanism enclosed and supported by said struc-

ture, and ground engaging members carried by said structure, whereby stresses caused by movement of the device over rough ground and by operation of said mechanism are transmitted to and taken up by said main supporting frame 5 structure.

16. In a mobile thresher, a main supporting frame consisting essentially of a substantially rigid unitary and hollow structure, thresher mechanism enclosed and supported by said structure, ground engaging members carried by said structure, and a grain bin supported on said structure and over the ground engaging members. 10

17. In a threshing machine, a substantially rigid metallic shell constituting both the main 15 supporting frame of the machine, and the housing and support for threshing mechanism.

18. In a mobile threshing machine, a combined threshing mechanism housing and main supporting frame consisting essentially of a substantially rigid metallic shell, ground engaging members carried by said shell, and threshing mechanism within and supported by said shell. 20

19. In a mobile thresher, a main supporting frame consisting essentially of a substantially rigid unitary and hollow structure of sheet metal, thresher mechanism enclosed and supported by said structure, said frame constituting substantially the sole support for said mechanism, and ground engaging members directly carried by 25 said structure, whereby stresses caused by movement of the device over rough ground and by operation of said mechanism are transmitted to and taken up by said main supporting frame 30 structure.

20. In a mobile thresher, a substantially rigid hollow structure of sheet metal, thresher mechanism enclosed and supported by said structure, said structure constituting both the main supporting frame of the machine and substantially 40 the sole support for said mechanism, ground engaging members, and means serving solely to connect said ground engaging members to said main supporting frame structure. 35

ELMER E. WICKERSHAM.
